UNITED STATES PATENT OFFICE.

JOHN H. SHAW, OF NEW HAVEN, CONNECTICUT, ASSIGNOR TO SARGENT & COMPANY, OF NEW HAVEN, CONNECTICUT, A CORPORATION OF CONNECTICUT.

MACHINE FOR LOADING CARTRIDGE BELTS AND THE LIKE.

Application filed November 23, 1918. Serial No. 263,900.

To all whom it may concern:

Be it known that I, JOHN H. SHAW, a citizen of the United States, residing in the city and county of New Haven, State of Connecticut, have invented certain new and useful Improvements in a Machine for Loading Cartridge Belts and the like, of which the following is a full, clear, and exact description.

10 This invention relates to a machine for loading cartridges into a belt, and more particularly to a machine for loading cartridges into a metal belt composed of a plurality of separate cartridge receiving links, 15 the links being constructed to be connected together by the cartridges inserted therein.

The primary object of my invention is to provide a small portable machine for loading cartridges and the like into belts, which machine consists of but few parts that may be quickly assembled for operation upon the battle-field, or other places, where it may be necessary to load cartridges into a belt.

Another object of my invention is to provide a cartridge belt loading machine, which is simple and compact in structure, in order that it may be easily transported from one place to another, and which is inexpensive to manufacture.

30 To these and other ends the invention consists of the novel features and combinations of parts to be hereinafter described and claimed.

In the accompanying drawings:

35 Fig. 1 is a side elevation of my loading machine shown mounted upon a board or the like.

Fig. 2 is a plan view of the same.

Fig. 2^A is a sectional view taken on the line 40 2^A—2^A of Fig. 2 looking in the direction of the arrows.

Fig. 3 is a bottom view of my device.

Fig. 4 is a front end view of my device.

45 Fig. 5 is a plan view of my loading machine, showing the position of the parts after forcing a plurality of cartridges into the cartridge receiving links of the belt.

Fig. 6 is an enlarged fragmentary view of part of the loading machine shown in 50 Fig. 5, showing the cartridges forced

through the cartridge receiving links, as in Fig. 5.

Fig. 7 is a longitudinal sectional view through the parts shown in Fig. 6, showing the position of the sliding bar and cartridges 55 before the cartridges are forced through the cartridge receiving links.

Fig. 8 is a sectional view taken on the line 8—8 of Fig. 6, and Fig. 9 is a side view of an operating handle shown removed from 60 the belt loading machine.

Several types of the more modern machine guns are constructed to receive cartridges from a metal belt formed of separate cartridge receiving links, each link having 65 somewhat of a double loop or figure 8 construction in cross-section. One of these loops is designed to receive one cartridge and the other loop to receive a second cartridge whereby a cartridge belt is formed in which 70 the links composing the same are connected together by the cartridges mounted therein. The important advantage of this form of cartridge belt is that when a loaded belt is passed through a machine gun, the belt disintegrates by the falling away of the links as the cartridges are removed from the same, so that there is no objectionable empty belt 75 dangling from the discharge side of the machine gun.

In the drawings I have illustrated a machine for loading cartridges into the type of link belt, above briefly described. This machine comprises a relatively flat base member or tray designated in its entirety by the 85 numeral 10, the same being somewhat rectangular in construction, as shown in Fig. 2. At the forward end of this tray is formed a lug 11 and at the rear end of the tray is formed a projection such as 12, the 90 projections 11 and 12 preferably have screw holes formed therethrough by means of which the tray 10 may be secured to a table or board such as 13. In the upper face of the tray 10 is preferably formed a plurality 95 of longitudinal grooves such as 14, which are constructed to receive the cartridges 15, which are to be loaded in the cartridge belt.

The forward end portion of the grooves 14 are preferably increased in width somewhat 100

as at 14' or in other words, the rib between two adjacent grooves 14 is reduced somewhat in order to form a satisfactory seat for the belt links 16, it being apparent that since 5 each link 16 is provided with two cartridge receiving openings, one of which lies in one of the grooves 14, and the other in the adjacent groove, the rib at this point should be of less width than the rib which separates that 10 portion of the grooves 14 in which the cartridges 15 lie. In order to prevent the links 16 from being displaced laterally when the cartridges are forced into the same, upwardly projecting lugs or abutments such 15 as 17 are preferably formed upon the tray 10, adjacent the forward end thereof. As shown in the drawings, these lugs are spaced apart a sufficient distance to permit the forward end of the cartridges to lie therebetween, as shown in Figs. 5 and 6, but prevent the links 16, in which the cartridges are inserted from being displaced laterally while the cartridge is forced into the same. It 20 will be understood that the construction of 25 the links 16 is such that the cartridges fit snugly into the same, so that they will not be accidentally removed from the link after having once been inserted in the same. Considerable force is therefore necessary to 30 properly seat the cartridges in the openings formed in the links. As above stated, each link of the cartridge belt has somewhat of a figure 8 construction in cross-section, whereby two loops or cartridge receiving openings 35 are formed, one of these loops is formed of two spaced cylindrical members 18, as shown in Fig. 6 of the drawing, and the other loop is formed of a single cylindrical member, such as 19, the construction being such that 40 the loop 19 of one link may be inserted between the loops 18 of the adjacent link, so that when a cartridge is inserted, it passes through both the loops 18 and 19, and thereby secures two adjacent links together. In 45 this manner the cartridge belt is composed of a plurality of independent links secured together by the cartridges. In forming the link 16, a portion such as 20 is formed to connect the loop portions 18 and 19 together. 50 This portion 20 is so positioned that when the cartridges are forced into the links, the portion 20 abuts against one of the lugs 17 and in this manner retains the link in place while the cartridge is being forced into the 55 same.

The means which I have provided for sliding the cartridges along the grooves 14 and into the cartridge receiving openings formed in the links 16, consists of a sliding bar 21. This bar preferably has a downwardly directed flange formed at each end thereof, such as 22, these flanges being positioned to contact with the opposite edges of the tray 10 and thereby retain the bar 21 in place as it is moved back and forth upon the

upper face of the tray. If desired, additional means may be provided for retaining the sliding bar in engagement with the tray, consisting of inwardly directed lugs 23, positioned to engage longitudinal slots formed 70 in the under face of the tray 10 as shown in Fig. 2A. In order to permit the bar 21 to be positioned upon the tray with the lugs 23 engaging the lower face of the same, notches 24 are cut in the opposite edges of the tray 75 10 to clear the lugs 23. The under face of the tray 10 is preferably provided with a plurality of lugs 23' in order that the tray will seat firmly upon the board or table 13 and also to provide a clearance space between the tray and the board for the sliding lugs 23. By this construction, it will be seen that the slide bar 21 may be moved back and forth over the face of the tray without becoming disengaged from the same. 80

The means which I have disclosed in the drawings for sliding the member 21 back and forth over the face of the tray 10 consists of a toothed rack 25, formed integral with the slide 21 and projecting rearwardly 90 therefrom. A handle member 26 is provided to cooperate with this rack, the same being pivotally mounted between a pair of upwardly projecting lugs 27 formed integral with the rearwardly projecting portion 12 of the tray 10. The handle 26 is provided with a plurality of teeth 28, formed in an arc of a circle, to cooperate with the teeth of the rack 25. The means for pivotally mounting the handle 26 between the upwardly projecting lugs 27, consists preferably of trunnions 29 projecting from the opposite sides of the handle and positioned to rest in bearing sockets formed in the lugs 27, the sockets being produced 105 by cutting notches in the upper face of these lugs, as shown at 30. By this arrangement it will be seen that the handle may be readily rotatably mounted between the lugs 27 in operative engagement with the rack and removed therefrom. In order to limit the extent to which the slide 21 may be moved towards the abutment or lugs 17 by its operating handle, I provide a downward projection 31 upon the rear 110 end of the rack 25, positioned to abut against the rear edge of the extension 12 and thereby prevent further movement of the slide 21. 115

The operation of my device is as follows: 120 When it is desired to load cartridges into a link belt of the type herein briefly described, a number of links are laid upon the tray 10, in their assembled position, as shown in Figs. 5 and 6: that is with the 125 loop portion 19 of one link extending between the spaced loop portions 18 of the adjacent link. The cartridges to be inserted in these links are then laid in the grooves 14 of the tray to one side of the 130

links just mentioned, whereupon the cartridges may be forced through the links as shown in Figs. 5 and 6 of the drawing by simply pressing down on the handle 26 to cause the sliding bar 21 to engage the rear end of the cartridges 15 and force the same into the links 16, the extent to which the cartridges are inserted in these links by the sliding bar 21 being limited by the stop 31 above mentioned. When a section of a cartridge belt of the type herein described has been formed by inserting cartridges into the link 16, this section may be moved to one side of the tray shown in the drawings and positioned so that the loop 18 or 19, which has not had a cartridge inserted therein, will lie in the slot 14 adjacent one side of the tray 10, whereupon the remaining slots of my tray may have placed therein a plurality of assembled links in position to have additional cartridges inserted therethrough. In this manner, the newly produced section of the cartridge belt may be connected up by a cartridge to that section which has been previously produced. It will, therefore, be seen that my machine for loading cartridges into a link cartridge belt or the like, may be quickly set up and put into operation wherever needed, it being simply necessary to mount the tray 10 upon a board or table, place the sliding bar 21 and the operating handle 26 in position, and then place a number of cartridges and cartridge receiving links in the grooves 14, whereupon a section of the cartridge belt will be produced by merely operating the handle to force a number of cartridges simultaneously into the links 16.

Although I have described my loading machine as designed particularly to load cartridges into a cartridge belt produced of independent metal links, it will be apparent that the device herein disclosed may be used to load cartridges into other types of belts, and that my invention is not limited to loading cartridges into the type of belt herein disclosed, and it will be apparent that the broad inventive idea disclosed in this application may be embodied in various mechanical means, for accomplishing the functions set forth, other than those used in the particular device shown in this application.

What I claim is:

1. A device for loading cartridges into a link belt, comprising a base member for supporting a plurality of links in their assembled position, abutments upon said member for preventing lateral displacement of said links, and a sliding bar for forcing cartridges into said links.

2. A device for loading cartridges into a link belt, comprising a grooved tray for supporting a plurality of links in their assembled position, said tray being pro-

vided with abutments for preventing lateral displacement of said links, said grooves serving to align cartridges with said links, and a sliding member for forcing said cartridges into said links. 70

3. A device for loading cartridges into a link belt, comprising a tray having a plurality of grooves formed therein for supporting cartridges in alignment with the links of a belt, abutments upon said tray 75 for preventing lateral displacement of said links, and means for forcing said cartridges into said links.

4. A portable tray for loading cartridges into a link belt, said tray having grooves 80 therein for supporting cartridges in alignment with a plurality of assembled links, means upon said tray for preventing lateral displacement of said links, and a sliding member for sliding said cartridges along 85 said grooves into said links.

5. In a device for loading cartridges into a link belt, a tray having grooves formed therein for supporting cartridges in alignment with a plurality of assembled links, 90 abutments for preventing lateral displacement of said links, a sliding bar for forcing said cartridges into said links, and manually operable means comprising a toothed rack and lever for operating said bar. 95

6. A tray for loading cartridges into a link belt, said tray having grooves formed therein to support a plurality of cartridges and cartridge receiving links in alignment with each other, abutments upon said tray 100 for preventing lateral displacement of said links, and a sliding member upon said tray for forcing cartridges into said links.

7. In a device for loading cartridges or the like into a belt, a tray for supporting a portion of said belt having grooves formed therein for supporting a plurality of cartridges in alignment with the cartridge receiving openings in said belt, abutments upon said tray for preventing lateral displacement of said belt, and a sliding member upon said tray for forcing said cartridges into said belt. 105

8. In a device for loading cartridges or the like into a belt, a base member for supporting a portion of said belt, said member having means for supporting a plurality of cartridges in alignment with the cartridge receiving openings formed in said belt, and a sliding member for forcing the cartridges 115 into said belt. 120

9. In a device for loading cartridges into a link belt, a small portable tray having a plurality of grooves formed therein for supporting a plurality of cartridge receiving links in their assembled position, said grooves serving also to guide cartridges into said links, abutments upon said tray for preventing lateral displacement of said links, a bar slidably mounted upon said tray 125 130

- for forcing said cartridges into said links, and manually operable means for operating said bar.
10. A cartridge-linking machine, comprising a plate grooved to space apart a plurality of cartridges and links, an abutment for said links and means for forcing the cartridges into said links.
11. A cartridge-linking machine, comprising a plate grooved to space apart in assembling relation to each other a plurality of cartridges and links, an abutment for the links and means consisting of a slidable bar and a connected lever for manually forcing the cartridges into the links.
12. A loading machine comprising a bed, grooves thereon to position a plurality of cartridges, means to support in overlapping relation a plurality of separate links in advance of the cartridges, stops at one edge of the bed, a pusher bar operating along the grooves, and means to operate the pusher bar.
13. A loading device comprising a bed, means thereon to position a plurality of links in overlapping relation and a plurality of cartridges, and means to limit movement of the links.
14. In a device of the character described, means for supporting a pair of links in position to be coupled by a cartridge, means for effecting the insertion of the cartridge in the coupling connection in said links, and means for limiting the movement of said second named means.
15. A loading device comprising a bed, means thereon to position a plurality of links in overlapping relation and a plurality of cartridges, and means to thrust the cartridges into the links.
16. A loading device comprising a bed, means thereon to position a plurality of links in overlapping relation and a plurality of cartridges, an abutment for the links, and means to thrust the cartridges into the links.
17. In a device of the character described, means for supporting a pair of links in position to be coupled by a cartridge, and means for effecting the insertion of the cartridge into coupling connection with said links.
18. A machine for loading cartridges into a disintegrating belt comprising a bed, means thereon to position the links of the belt and the cartridges, means to thrust the cartridges into the links, and means to vary the scope of movement of said thrusting means.
19. In a loading machine, holding means for the receptacles for the articles to be loaded, means to position said articles, a pusher to force the articles into the receptacles, and means having a variable connection therewith to operate said pusher means.
20. In a loading device, means for po-
- sitioning a series of separate links and a series of cartridges, means for producing relative movement between the members of one series and the members of the other series to couple the links together by the cartridges.
21. A loading machine comprising a bed, means thereon to position a plurality of cartridges and links in assembling relation, an abutment for the links, a pusher to move the cartridges into the links, and a pusher operating means mounted upon the bed and operatively connected to the pusher.
22. A loading machine comprising a bed, means thereon to position a series of cartridges and a series of links in assembling relation, means to limit the movement of one series, and means to move the members of the other series relatively to the members of the first series to effect a coupling connection of the cartridges and links.
23. In a loading machine, a bed, means thereon to position a plurality of links and cartridges slotted brackets upon the bed, a reciprocating pusher bar, and means mounted in the slots in said brackets to operate said bar.
24. In a device of the character described, means for supporting a pair of separate links and a cartridge in assembling relation, a pusher for moving the cartridge into the links, and means for operating said pusher.
25. In a loading machine, a bed, means thereon to position a plurality of separate links and cartridges in assembling relation, and a guided pusher bar to push the cartridges into the links.
26. A loading machine comprising a bed, means thereon to position a plurality of links in overlapping relation and a plurality of cartridges, a pusher bar, a toothed rack connected to said bar, means engaging the teeth of the rack to operate the bar, and means for limiting the movement of the pusher.
27. A loading device comprising a bed having grooves to position a plurality of cartridges, means for supporting a plurality of links in alignment with the cartridges, an abutment for the links, a slide for thrusting the cartridges into the links having a rearwardly directed bar secured thereto, and operating means mounted upon the bed and engaging said bar.
28. A loading device comprising a bed having grooves to position a plurality of cartridges, means for supporting a plurality of links in alignment with the cartridges, an abutment for the links, a slide for thrusting the cartridges into the links having a rearwardly directed bar secured thereto, a pair of brackets mounted upon the bed between which the bar is mounted, and operating means for the pusher mounted on said brackets.

29. A loading device comprising a bed having grooves to position a plurality of cartridges, means for supporting a plurality of links in alignment with the cartridges, an abutment for the links, a slide for thrusting the cartridges into the links having a rearwardly directed bar secured thereto, a pair of brackets mounted upon the bed be-
- tween which the bar is mounted, operating means for the pusher mounted on said brackets, and a stop upon said bar to limit the movement of the thrusting means.
- In witness whereof, I have hereunto set my hand on the 20th day of November, 1918.

JOHN H. SHAW.
